United States Patent Office.

THOMAS S. SLEEPER, OF BINGHAMTON, NEW YORK.

Letters Patent No. 95,279, dated September 28, 1869.

IMPROVED AXLE-SKEIN.

The Schedule referred to in these Letters Patent and making part of the same.

To all whom it may concern:

Be it known that I, THOMAS S. SLEEPER, of Binghamton, in the county of Broome, and State of New York, have invented a new and improved Mode of Constructing Skeins for Wagon Axle-Tree Spindles; and I do hereby declare that the following is a full and exact description thereof, reference being had to the accompanying drawings, and to the letters of reference marked thereon.

Figure 1 is a transverse longitudinal section, showing the inside angles of the skein.

Figure 2 is a perspective view, representing the mouth on increased angle.

Similar letters of reference indicate like parts in each figure.

The nature of my invention consists in the construction of a skein for wagon axle-tree spindles, prepared by machinery, with a mouth of increased capacity from the inner shoulder of the bearing-surface, to receive a greater thickness of timber, thereby obviating the liability to break the spindle.

I construct the socket of my skein A with a continuous angle from the shoulder-nut B to the inner shoulder C of the bearing, the angle of which I make slightly less than that of the ordinary skein, thereby giving it a more natural bearing in the box.

I then increase the angle from the shoulder C to the end D, for the purpose of increasing the strength of the spindle at a point where it is most liable to break when sheathed with the ordinary skein.

The skein patented by Cornelius Campbell, July 11, 1867, has a continuous angle through its entire length, with a view to accomplish the same result, and it has proved a failure, while my invention fully accomplishes the object.

My improvement is designed for spindles fitted by the machine patented by Cornelius Campbell, October 9, 1866, with the exception of an improved guide-plate for turning the increased angle.

I do not claim broadly an increased or disproportionate enlargement of the socket of the skein beyond or inside of that portion of the skein upon which the box bears, as that feature is shown in the patent of R. W. McGrath, dated January 28, 1868, as well as in many of earlier date, but it will be apparent that a skein of such construction cannot be reversed when the lower side shall have become worn.

Having thus described my invention,

What I claim, and desire to secure by Letters Patent, is—

An axle-skein, the socket of which is increased in diameter at a uniform angle from the outer end B to the collar C, and is expanded on two or more sides of its axial centre, at an increased angle from the collar C to the mouth D, substantially as and for the purpose set forth.

THOS. S. SLEEPER.
